UNITED STATES PATENT OFFICE.

JOSEF LEHNE, OF TEMPELHOF, AND WILHELM LUCKE, OF NEUKÖLLN, BERLIN, GERMANY, ASSIGNORS TO INTERNATIONALE ROTATIONSMASCHINEN-GESELLSCHAFT MIT BESCHRÄNKTER HAFTUNG, OF BERLIN, GERMANY.

CENTRIFUGAL PUMP.

1,139,042.

Specification of Letters Patent. Patented May 11, 1915.

Application filed April 10, 1914. Serial No. 830,918.

To all whom it may concern:

Be it known that we, JOSEF LEHNE, a subject of the Grand Duke of Hesse, and residing at Tempelhof, Berlin, Germany, and 5 WILHELM LUCKE, a subject of the King of Prussia, and residing at Neukölln, Berlin, Germany, have invented certain new and useful Improvements in Centrifugal Pumps, of which the following is a specification.

10 The subject of this invention is an improved centrifugal pump of that class which combines the advantages of a centrifugal pump with those of a piston pump, that is to say, a pump which has a purely rotary motion, is of simple construction, is little affected by impurities and has a high efficiency, and at the same time sucks also when the induction pipe is not filled.

The main feature of the invention is that 20 an auxiliary device, which enables automatic suction, can be brought out of operation, so that the pump then acts under wholly normal conditions. Should the suction stream be interrupted, the auxiliary device can be thrown in again, either by hand 25 or automatically.

Certain forms of construction of the new pump are illustrated in the accompanying drawings.

30 Figure 1 is a side elevation of one form of the improved pump. Fig. 2 is a longitudinal section through the same. Fig. 3 is a cross section through Fig. 2, the valve being shown turned through 90 degrees.

35 Fig. 4 is a longitudinal section and part elevation of a modification, drawn to a larger scale. Fig. 5 is a section on the line A—B of Fig. 4, the valve being shown turned through 90 degrees.

40 The wheel or runner α of the centrifugal pump is mounted in the ordinary way in a casing b . If the delivery pipe c is closed and water is contained in the pump, while the suction pipe d is empty, there will be formed 45 in the casing b , under the influence of the centrifugal force, a ring of water, which revolves eccentrically with the blade wheel and as is well-known works together with the wheel in the manner of a rotary pump, 50 the water at different parts of the periphery entering the cells, constituted by the blades and side walls, to different depths, so that suction spaces are formed.

In the interior of the wheel α there is an

axially slidable valve e provided, which lies 5: concentric with the wheel and is of such construction that the side of the wheel on which there is an enlargement of the cell spaces, is in communication with the suction pipe of the pump, while the air which has been 60 sucked in is driven out to the atmosphere through a passage f in the valve and through an exit g (Figs. 1-3). Immediately water is seen in the exit g —which shows that the suction pipe is full—the valve e is withdrawn from the wheel α , so that the pump now works as an ordinary centrifugal pump. The exit g is now cut off from the suction pipe. The axial shifting of the valve e is 65 effected by means of a rod e^1 and system of 70 levers e^2 . For the purpose of insuring good closure, a back pressure valve, opening outward, may be provided in the exit g .

Referring to the modification illustrated in Figs. 4 and 5, the pump casing b with 75 suction and delivery pipes d , c , is of such construction that the valve e can be wholly removed from the suction stream. When working normally, the water entering the wheel α does not pass through the valve e 80 at all. In this case a back pressure valve g^1 must be provided for the aperture g , which valve on discharging is closed automatically by the external air pressure, while on sucking it is opened by the internal over-pressure, so that the air pumped can escape 85 from the suction pipe.

In cases in which it is desired that the pump structure shall be as compact as possible, it is preferable only partly to remove 90 the valve e from the suction stream. In this event the valve is furnished at a suitable place with an aperture of such cross section that on normal working commencing there is ample passage for unobstructed flow of 95 the suction stream. In addition to this, the valve is then made open internally, and the wheel is not balanced, as is customary, by the provision of holes. In this manner flow outside the wheel from the discharge to the 100 suction chamber is prevented.

The valve e can be actuated by means, for instance, of a screw spindle h and a crank handle i , a hand wheel or the like; or it may be operated automatically as soon as the 105 pump is sufficiently evacuated.

When the valve is entirely removed from the suction stream, it is not possible, on the

suction passage being closed by the sliding valve, to prevent a part of the water, which fills the pump casing, being shut in and so offering resistance to the further axial motion of the valve. To obviate this drawback a groove *k* is provided in the wall of the casing, which groove in the position of the valve in which the suction passage is closed, allows escape of the confined water. Whereas with the wheel casings in prior centrifugal pumps the spiral which the wheel describes is enlarged in radial direction, according to the present invention the cross section of the spiral exhibits an extension in axial direction, as indicated at *m* (Fig. 4). The advantage of this is that the ring of water is compelled to move inside the wheel, whereby the air is directed into the exit and clearance spaces are avoided. The same end is promoted by the special construction of the chamber for the wheel. As shown in Fig. 5, the initial part of the inner circumferential wall of the chamber runs (as indicated by the line *x-y*) concentrically with the wheel, so that the ring of water is caused to contact with the valve over a considerable distance, whereby the air drawn in is effectively forced out of the exit. The various forms of construction may by the addition of further normal guide wheel pumps also be built as high pressure pumps.

Having thus described our invention, we declare that what we claim as new is—

1. In a centrifugal pump, in combination, a casing having a suction inlet and a delivery outlet and an air exit, a revoluble blade wheel mounted in the casing, and an axially slidable valve located concentrically with the wheel and which when slid within the latter connects one part of the wheel with the said suction inlet and another part with the said air exit.

2. In a centrifugal pump, in combination, a casing having a suction inlet and a delivery outlet and an air exit, and a valve controlling the latter, a revoluble blade wheel mounted in the casing, and an axially

slidable valve located concentrically with the wheel and which when slid within the latter connects one part of the wheel with the suction inlet and another part with the said air exit. 50

3. In a centrifugal pump, in combination, a casing having a suction inlet and a delivery outlet and an air exit, a revoluble blade 55 wheel mounted in the casing, and an axially slidable valve located concentrically with the wheel and which when slid within the latter connects one part of the wheel with the suction inlet and another part with the said air exit, said casing also having a groove which, when the valve on being slid out of the wheel closes the suction inlet, constitutes a fluid passage between the space behind the valve and the suction inlet. 65

4. In a centrifugal pump, in combination, a casing having a suction inlet and a delivery outlet and an air exit, a revoluble blade wheel mounted in the casing, and an axially slidable valve located concentrically with the 70 wheel and which when slid within the latter connects one part of the wheel with the suction inlet and another part with the said air exit, the cross section of the spiral which the wheel describes moreover exhibiting an 75 extension in axial direction.

5. In a centrifugal pump, in combination, a casing having a suction inlet and a delivery outlet and an air exit, a revoluble blade 80 wheel mounted in the casing, and an axially slidable valve located concentrically with the wheel and which when slid within the latter connects one part of the wheel with the suction inlet and another part with the said air exit, the initial part of the inner circumferential wall of the wheel chamber running 85 concentrically with the wheel.

In testimony whereof we affix our signatures in presence of two witnesses.

JOSEF LEHNE.
WILHELM LUCKE.
